UNITED STATES PATENT OFFICE

2,159,458

REFLECTING MARKER

Hugh W. Stoddard, Dallas, Tex.

Application April 11, 1938, Serial No. 201,351

2 Claims. (Cl. 40—125)

My invention relates to location indicators, particularly to markers for the guidance of motorists.

Various types of light-reflecting elements have been employed on location-indicating devices to derive luminosity from automobile or street lights. The general object of the present invention is to provide, in combination with such a light-reflecting element, a standard or support that serves as an efficient mounting for the element, and cooperates with the element in the role of marking a location.

One object of my invention is to provide a marker standard that lends itself to efficient anchorage in soil or other supporting material. A feature sought in my invention is a choice of two visible configurations for the marker to be had merely by selecting the depth to which the marker is buried in the supporting material.

A further object in mind is to provide a durable but low-cost construction for a marker.

The above and other objects and advantages will be apparent in my detailed description to follow, considered with the accompanying drawing.

In the drawing:

Fig. 1 is a front elevation of one form of my marker;

Fig. 2 is a side elevational view;

Fig. 3 is a plan view of the marker;

Fig. 4 is a front elevation of a second form of my marker; and

Fig. 5 is a fragmentary side view of the marker shown in Fig. 4.

Figs. 1 to 3 show a metal standard cast in one piece, the standard having at its upper end a cylindrical portion 10 to seat a pair of oppositely directed light-reflecting elements 11. In the usual installation such a marker is placed at a roadside with the axis of the light-reflecting elements disposed substantially in the direction of travel.

Integral with and encompassing the cylindrical portion 10 of the standard is a pair of lateral flanges 12 in a plane substantially perpendicular to the light-reflecting axis. The two lateral flanges 12, considered together, have an upper portion 13 that slightly widens from top to bottom, an intermediate portion 14 that widens to a marked degree, and finally a lower portion 15 that forms a pair of relatively extensive lateral wings 16. Also integral with and extending downward from the cylindrical portion 10 of the standard is a second pair of vertical flanges 17, preferably approximately in the plane through

the light-reflecting axis. The two flanges 17 do not protrude extensively and may be of uniform cross-section; in fact, in my preferred configuration shown in the drawing, these two flanges may aptly be termed "ribs." At the bottom of the standard the two sets of vertical flanges terminate in a pair of horizontal flanges 18.

The marker standard is by preference painted white, or white with black stripes, and is buried in the ground either to a point above the level 19 or between that level and a level 20 depending upon whether the visible configuration desired is that of the upper portion 13, or that of the upper portion 13 together with the intermediate portion 14 of the marker. One function of the pair of flanges 12 is to provide a desired extent of visible surface.

A second function of the lateral flanges 12, particularly the lowermost portions thereof, is to provide to a major extent the anchorage for the marker. Cooperating therewith as anchorage means are the flanges 17 and the flanges 18. Both of these flanges 17 and 18 resist any stresses against the embedded standard in the plane of flanges 12, and flange 18 also resists any force tending to lift the embedded standard vertically.

The light-reflecting elements 11 may be of any type known to the art, but I contemplate using elements that tend to diffuse light over the body of the reflector. In the preferred form of my invention, for example, I may employ the light-reflecting elements disclosed in the Bone Patent No. 1,872,643.

The second form of my invention shown in Figs. 4 and 5 is similar to the form just described with the addition of a sign panel 21. This sign panel 21 is located below and adjacent the cylindrical portion 10a of the standard and is both integral with and in the same plane with the lateral flanges 12a of the standard. Preferably both faces of the panel 21 are framed by marginal flanges 22, the front and rear ribs 17a connecting therewith. This second standard, like the first, may be anchored in the ground by the two wing portions 16a, the ribs 17a, and the bottom flanges 18a.

Indicia such as shown at 23 in Fig. 4 are painted on the panel 21, preferably against a white background, and are illuminated by light diffused from the reflecting elements 11.

The two preferred forms of my invention shown and described in detail will suggest to those skilled in the art various changes and mod-

ifications that do not depart from the essence of my conception. I reserve the right to all such changes and modifications that properly come within the scope of my appended claims.

5 I claim as my invention:

1. In a marker of the character described, the combination with a pair of oppositely disposed coaxial light-reflecting elements of a cast metal supporting body adapted to be partially embedded in soil or the like, said body having: a cylindrical portion housing said elements; vertical flanges perpendicular to the axis of said elements to provide light-reflecting surfaces on opposite sides of the body, the lower portions of said flanges being widened to provide the major anchorage for the body; vertical flanges in the plane of said axis to cooperate in anchoring the body; and horizontal flanges at the lower end of

the body to oppose any force tending to withdraw the body from an embedded position.

2. A luminous sign of the character described, having a pair of oppositely disposed coaxial light-reflecting elements in combination with a cast metal supporting body, said body comprising: a cylindrical portion housing said elements; a panel portion for indicia adjacent thereto; vertical flanges perpendicular to the axis of said elements, said flanges being widened at the lower portions thereof to provide anchorage for the body when embedded in soil or the like; vertical flanges in the plane of said axis to cooperate with the first-named flanges in anchoring the body; and a horizontal flange at the lower end of the body to oppose any force tending to withdraw the body from an anchored position.

10 15 HUGH W. STODDARD.
